THE NATIONAL LITHOGRAPHIC COMPANY,
WASHINGTON, D. C.

UNITED STATES PATENT OFFICE.

WILLIAM H. HART, OF NEW BRITAIN, CONNECTICUT.

DESIGN FOR A STRAP-HINGE.

SPECIFICATION forming part of Design No. 23,402, dated June 26, 1894.

Application filed May 9, 1894. Serial No. 510,662. Term of patent 14 years.

To all whom it may concern:

Be it known that I, WILLIAM H. HART, a citizen of the United States, residing at New Britain, county of Hartford, and State of Connecticut, have invented and produced a new and original Design for Strap-Hinges, of which the following is a specification.

My new and original design is illustrated by the accompanying drawing, in which a plan view of a strap hinge is shown.

The leading feature of my design consists in a strap-hinge, one leaf of which being of tapering U-shape, the other or companion leaf being of substantially an outline correspond-

A is a tapering U-shaped hinge-leaf.
B is a companion leaf, the contour of which corresponds substantially to the inner edge of the leaf A, the broader ends of the said leaves A and B coming together as shown. 20

What I claim is—

The design for a strap-hinge, substantially as herein shown and described.

WILLIAM H. HART.
